UNITED STATES PATENT OFFICE.

WILLIAM HOOKER ATWOOD, OF NEW HAVEN, CONNECTICUT.

DESIGN FOR AN AUTOMOBILE-BODY.

No. 37,952.

Specification for Design.

Patented April 10, 1906.

Application filed March 12, 1906. Serial No. 305,722. Term of patent 14 years.

To all whom it may concern:

Be it known that I, WILLIAM HOOKER ATWOOD, a citizen of the United States, residing in the city and county of New Haven, State of Connecticut, have invented a new, original, and ornamental Design for an Automobile-Body, reference being had to the accompanying drawing, in which the figure is a side elevation, partly in perspective, of my newly-designed automobile-body.

What I claim is—

The ornamental design for an automobile-body, as shown.

WILLIAM HOOKER ATWOOD.
